DOUBLE ADJUSTABLE BINDER

Brooks Fleming Ellis, White Plains, N. Y., assignor to Federbush Co., Inc., New York, N. Y.

Application October 17, 1941, Serial No. 415,443

4 Claims. (Cl. 129—13)

This invention relates to new and useful improvements in a double adjustable binder.

The invention proposes certain improvements in a binder having a back, and separate front and back covers having their inner edge portions extending over the inner faces and sides of said back. The improvements include a rib on the inner face of said back between the sides thereof and extending inward between the inner edges of said covers. It is proposed that transverse studs for passing through perforations of pages for said binder be mounted in said rib. It is proposed that angle irons on flexible strips be mounted on the inner edge portion of said covers for extending over the back corners of the pages of said binder and for extending over the ends of said studs. It is also proposed that fastening elements be mounted on said studs for securing said flexible strips in position. Furthermore, it is proposed to provide certain of the arms of the said angle irons with stacking pins for engaging perforations of the pages of the binder.

Another object of the invention resides in the provision of means for releasably securing the inner edges of said flexible strips on the sides of said rib.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a binder constructed in accordance with this invention and viewed from the back.

Fig. 2 is a perspective view of the binder shown in Fig. 1 but looking from the front.

Fig. 3 is a fragmentary horizontal enlarged sectional view taken on the line 3—3 of Fig. 2.

Fig. 4 is a fragmentary vertical sectional view taken on the line 4—4 of Fig. 3.

Fig. 5 is a view similar to Fig. 3 but with the connecting strips removed.

Fig. 6 is a perspective view of one of the studs used in the binder.

Fig. 7 is a perspective view of another stud for the binder.

The double adjustable binder, in accordance with this invention, has a back 10, and separate front and back covers 11 and 12 respectively. These covers have their inner edge portions 11^a and 12^a, respectively, extended over the inner face and sides of the back 10. A rib 13 is on the inner

face of the back 10 and is located between the sides thereof, preferably intermediate of the width of the back. This rib 13 extends inward, in between the inner edge portions 11^a and 12^a of the covers. The back 10 is ornamented with a sheet leather covering 14, or other decorative material.

A plurality of transverse studs 15 for passing through perforations 16 in pages 17 for the binder, are mounted on the said rib 13. Each stud 15 is formed from two sections connected together. There is a right hand section 18 having a reduced threaded end 19 which passes through an opening in the rib 13 and which threadedly engages a tubular left hand section 20. The sections 18 and 20 are formed with several radial perforations 21 into which a nail or other tool may be engaged for conveniently gripping the sections so that they may be turned to engage or disengage the threads of the stud 15.

The inner edge portions 11^a and 12^a of the covers are joined with the material of the covers by flexible portions at the points 22. Angle members 30 are mounted by one of their arms, their base arms, upon the edge portions 11^a and 12^a of the covers so that their other arms, their extended arms, may extend along the outer faces of the pages 17 of the binder. The extended arms of the angle members 30 also extend over the free ends of the studs 15. Fastening elements, such as headed screws 23, are mounted through apertures 30^d in the extended arms of the angle members 30 and threadedly engage the outer ends of the studs 15 to rigidly hold the angle members 30 in position relative to the back 10. It should be noted that the covers 11 and 12 may be opened and closed because of the flexible portions 22. The extended arms of the angle members 30 are also provided with several inwardly projecting stacking pins 24 which engage additional perforations 16 in the pages 17.

The covers 11 and 12 are each constructed with several internal stiffening layers 31 which are encased by an outer covering sheet 32 and an inner covering sheet 33. The outer covering sheet 32 continues past the inner edge of the stiffening sheets 31 and continues around the base arms of the angle members 30 terminating at the points 32^a.

Covering strips 34 are mounted over the extended arms of the angle members 30 and continue over the inner edge portions of the stiffening layers 31 and terminates at the points 34^a. The inner covering sheets 33 engage over the edge portions of the stiffening layers 31 at the

points 34^a, as clearly seen for example, in Fig. 3. Means is provided for releasably securing the inner edges of the covers onto the sides of the rib 13. This means is shown to comprise a plurality of spacer strips 26 extending substantially the height of the back 16 and connected with the sides of the rib 13 and with the inner edges of the covers 11 and 12. The spacer strips 26 are provided with dove-tailed tongues 27 on one of their sides which engage complementary grooves, either upon the sides of the rib 13 or on adjacent sides of the spacer strips. The inner edges of the covers 11 and 12 are formed with similar dove-tailed tongues engaging certain of the spacer strips.

The operation of the binder may be understood from the following:

The screws 23 may be removed to free the covers 11 and 12. Then the loose leaf pages 17 may be stacked upon or removed from the stacking pins 24. The covers 11 and 12 may be re-connected with the back 10 by moving the stacked pages 17 so that the studs 15 engage through the complementary perforations 16 of pages 17. Then the screws 23 are re-engaged with the ends of the studs 15. It should be particularly noted that the angle members 30 protect the inner corners of the pages 17. The covers 11 and 12 may be opened and closed because of the flexible areas 22. The flexible areas 22 comprise merely adjacent portions of the covering sheets 32 and 34.

In Fig. 7 a shorter stud 15' is illustrated to indicate that the rib 13 may be provided with transverse studs of desirable lengths, depending upon the number of pages 17 for the binder. When the number of pages are increased it is desirable that the studs be replaced with longer studs, and when pages are removed, smaller studs should be used.

The covers 11 and 12 may be supported in various laterally extended positions on the rib 13 by adding or removing spacer strips 26. This arrangement permits adjustment to be made to better compensate the pages 17 of the binder. If the binder is provided with a large number of pages 17 additional spacer strips 26 are added, and if pages are removed then spacer strips 26 are removed.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a binder having a back and separate front and back covers for enclosing loose leaves, a rib on the inner face of said back between the sides thereof and projected forwards between said loose leaves, transverse studs projecting from the sides of said rib and extending through aligned openings in said loose leaves and formed with threaded openings extended inwards from their free ends, angle irons having one of their arms freely projected towards each other across the inner face of said back and their other arms projected forwards over the face of the outermost leaves and over the free ends of said studs, each of said covers having its back edge pivotally attached to one of said angle irons at the junction of said arms, and headed screws passing freely through openings formed in the forwardly ex-

tending arms of said angle members and threadedly into the threaded openings in said studs for clamping the back edges of said leaves in position between the adjacent faces of said rib and the forwardly extending arms of said angle irons, and means for releasably securing the edges of the arms of said angle irons which extend along the inner face of said back to the sides of said rib.

- 11.5. 2. In a binder having a back and separate front and back covers for enclosing loose leaves, a rib on the inner face of said back between the sides thereof and projected forwards between said loose leaves, transverse studs projecting from the sides of said rib and extending through aligned openings in said loose leaves and formed with threaded openings extended inwards from their free ends, angle irons having one of their arms freely projected towards each other across the inner face of said back and their other arms projected forwards over the face of the outermost leaves and over the free ends of said studs, each of said covers having its back edge pivotally attached to one of said angle irons at the junction of said arms, and headed screws passing freely through openings formed in the forwardly extending arms of said angle members and threaded into the threaded openings in said studs for clamping the back edges of said leaves in position between the adjacent faces of said rib and the forwardly extending arms of said angle irons, and means for releasably securing the edges of the arms of said angle irons which extend along the inner face of said back to the sides of said rib, comprising strips removably connected with each other and with the inner edges of the arms of said angle members and the sides of said rib.

3. In a binder having a back and separate front and back covers for the enclosing loose leaves, a rib on the inner face of said back between the sides thereof and projected forwards between said loose leaves, transverse studs projecting from the sides of said rib and extending through aligned openings in said loose leaves and formed with threaded openings extended inwards from their free ends, angle irons having one of their arms freely projected towards each other across the inner face of said back and their other arms projected forwards over the face of the outermost leaves and over the free ends of said studs, each of said covers having its back edge pivotally attached to one of said angle irons at the junction of said arms, and headed screws passing freely through openings formed in the forwardly extending arms of said angle members and threaded into the threaded openings in said studs for clamping the back edges of said leaves in position between the adjacent faces of said rib and the forwardly extending arms of said angle irons, and means for releasably securing the edges of the arms of said angle irons which extend along the inner face of said back to the sides of said rib, comprising strips removably connected with each other and with the inner edges of the arms of said angle members and the sides of said rib, certain of said strips being removable permitting the remaining strips to be connected together for holding said angle irons in various spaced positions relative to said rib to accommodate stacks of loose leaves of different thicknesses.

4. In a binder having a back and separate front and back covers for enclosing loose leaves, a rib on the inner face of said back between the sides thereof and projected forwards between said

loose leaves, transverse studs projecting from the sides of said rib and extending through aligned openings in said loose leaves and formed with threaded openings extended inwards from their free ends, angle irons having one of their arms freely projected towards each other across the inner face of said back and their other arms projected forwards over the face of the outermost leaves and over the free ends of said studs, each of said covers having its back edge pivotally attached to one of said angle irons at the junction of said arms, and headed screws passing freely through openings formed in the forwardly ex-

tending arms of said angle members and threadedly into the threaded openings in said studs for clamping the back edges of said leaves in position between the adjacent faces of said rib and the forwardly extending arms of said angle irons, and means for releasably securing the edges of the arms of said angle irons which extend along the inner face of said back to the sides of said rib, said removable connection, comprising complementary interengaging dove-tailed tongues and grooves formed on the adjacent faces of said strips, angle irons and rib.
